CLAIM

The new and ornamental design for a headlight, as shown and described.

DESCRIPTION

FIG. 1 is a front elevation of a headlight showing a first embodiment of my new design,

FIG. 2 is a front elevation of a right headlight showing a second embodiment of my new design,

FIG. 3 is a front elevation of a left headlight showing a third embodiment of my new design; and,

FIG. 4 is a view taken from the front and left side thereof, installed in a tractor, with the broken line showing for illustrative purposes only and forming no part of the claimed design.
